UNITED STATES PATENT OFFICE.

BROWNLOW STARBUCK, OF PEORIA, ILLINOIS, ASSIGNOR OF ONE-HALF TO WILLIAM E. KINSEY, OF PEORIA, ILLINOIS.

NIPPLE-HOLDER.

1,124,546.

Specification of Letters Patent.

Patented Jan. 12, 1915.

Application filed May 10, 1913. Serial No. 766,885.

To all whom it may concern:

Be it known that I, BROWNLOW STARBUCK, citizen of the United States, residing at Peoria, in the county of Peoria and State of Illinois, have invented certain new and useful Improvements in Nipple-Holders; and I do hereby declare that the following is a full, clear, and exact description of the invention, which will enable others skilled 10 in the art to which it appertains to make and use the same.

This invention relates to a nipple holder or nipple chuck.

The object of the invention is to provide 15 a device that will securely hold a short piece of pipe or nipple which it is desired to furnish with a screw thread by means of the customary appliances for so doing, for instance a die, thread cutting machine, or ordinary lathe, or to otherwise work upon said nipple.

Another object is to provide a device that will securely hold the nipple from turning in either direction, and particularly for 25 holding it from locking in the die when the latter is reversed after having cut the thread.

Another object is to provide a device that will absolutely hold a nipple from turning 30 in either direction during the time the thread is being cut and at the same time will quickly release the nipple.

Still another object is to furnish a nipple holder of a very simple construction that 35 while adapted to firmly hold a nipple while cutting a thread, at the same time will quickly release said nipple without danger to its threads or to any part of the holder.

In the accompanying drawing illustrating 40 the invention, Figure 1 is a side elevation of the main portion of the holder. Fig. 2 is a longitudinal section of a sleeve to engage the same. Fig. 3 shows a holder completely assembled and a nipple held therein. Fig. 4 45 is a transverse section of the main portion of the holder on line *a a*, Fig. 3, as seen in the direction of the dart, and Fig. 5 shows a disk in perspective.

Before entering upon a detailed description 50 of my nipple-holder I wish to state that

I am aware of nipple holders of various types some of which have in view, as in the present instance, the desire to form an absolute chuck for the nipple for preventing the same turning while being operated upon. 55 But these, in most cases, require somewhat complicated structures which do not permit the nipple to be readily removed from the holder without damage to both the nipple and the holder. Other devices of which I 60 am aware require parts that easily become lost and for that reason are very unsatisfactory and in view of the trouble experienced in properly holding the nipple while receiving its thread, and of the difficulty in releasing said nipple in the forms of holders now in use, I have devised an improved nipple holder now to be described which has the advantage of firmly holding the nipple from turning in either direction and permitting 65 the nipple to be instantly released; there being no keys or extra parts to become detached and lost.

In the drawing, A represents the main portion of my holder which consists of a 75 stem to be inserted into a lathe chuck or other holding means, not shown, and having cut at one end a heavy square thread B and including near the base of said thread a stop C clearly shown in Figs. 1, 3 and 4. 80

D is a sleeve provided interiorly with a square thread E corresponding to the thread B of the stem A and adapted to engage the same as shown in Fig. 3. The thread E ends abruptly at F within the sleeve at its 85 outer end, see Figs. 2 and 4, being adapted to meet the stop C, the latter in use preventing turning of the stem and sleeve further upon one another after being screwed home. The opposite end of the sleeve D is provided 90 interiorly with screw threads G of the ordinary pointed type or that form of thread corresponding in form and pitch to the standard threads of the nipple H or other member being threaded.

J is a disk having a position, in use, within the sleeve D and adapted to rest upon the end of the stem A to receive the pressure of the end of the nipple H. In practice the sleeve is screwed upon the stem 100

2
 A as far as it will go, the terminal F of the thread E bearing against the pin C. The nipple is then screwed into place in the sleeve against the disk J the relative position being clearly illustrated in Fig. 3. All operations upon the nipple H may now be performed, the threads of the nipple firmly chucking into the threads of the sleeve due to the strain applied by the threading or other tool, and the limiting of movement endwise by the disk J.

As distinguished from those types of nipple holders of which I am aware, my device as shown and described in which the sleeve is really a union for the nipple and stem A includes a part provided both with standard pointed thread and with a second dissimilar thread preferably the square thread E described. The advantage of this structure is that while the standard thread is necessary for the nipple, a heavy or much coarser and preferably a square thread used to engage the stem cannot become jammed or crossed with the thread of the stem since a turn sufficient to properly lock the threads of the nipple and threads G would not be sufficient to cause the coarser threads to lock, particularly if of a square form as B. In the square form with a straight side which lies perpendicular to the axis of the stem and sleeve it is practically impossible for the sleeve and the stem to become locked even to the slightest extent when making use of the pin C or other equivalent form of stop on the stem with which the end of the thread E is caused to engage.

In practice, the nipple under the most severe strain that can be placed upon it, which causes it to seat so tightly in the sleeve as to require special means to release it, can be very readily moved by a simple hand grasp to turn the sleeve and the stem relatively. By reason of the fact that the dissimilar larger threads B, E, particularly if square do not become locked into one another in the manner that the standard threads of the sleeve do, admits of the sleeve being turned relatively to the stem with no effort whatever. When the pressure of the disk J upon the nipple is removed, therefore, the latter can be very easily removed.

Where a member is furnished at opposite ends with the same kind of thread for receiving two members abutting upon one another, both the latter become so firmly wedged or locked as to require the special tools mentioned. The dissimilar threads, however, one a square thread, in conjunction with a stop such as C, and preferably employing the disk J, absolutely prevents the locking or wedging. The stop C extends laterally from the stem so as to abut upon the end of the thread at F so that there can

be no possible chance for the two parts A and D becoming locked as might result were 65 the part D permitted to abut upon a shoulder of A such as that adjacent the said stop C. Therefore, the stop extends from the part A substantially perpendicular to the longest axis of the latter to best serve its 70 purpose.

Slight changes are possible in the construction of my nipple-holder such as would lie within the meaning and the invention and its claims.

75

Having described my invention, I claim:—

1. A nipple holder comprising a sleeve threaded internally at one end to receive the part to be machined and provided at its other end with a thread of dissimilar form, 80 a member provided with a thread corresponding to and adapted to engage the latter thread, a laterally extending stop on the member and the sleeve lying in the path of rotation of one another to limit the rotation 85 of the said sleeve and member relatively.

2. A nipple holder including a sleeve threaded internally at one end to receive the work to be handled and provided at its end with a thread of a different pitch, a member correspondingly threaded to engage the last named thread, a stop projecting from one of the surfaces of the member, and a stop on the sleeve, one of said stops adapted to move into the path of the other in the 90 rotation of the parts relatively.

3. A nipple holder including a sleeve threaded to receive the work to be treated, a member having threaded engagement with the sleeve, a stop on the member, and a stop 100 on the sleeve adapted to be moved into the path of and to engage one another in the rotation of the parts relatively.

4. A nipple holder consisting of a sleeve internally threaded at one end and adapted 105 to receive a nipple at that end and having a square form of thread at its other end, a member provided with a corresponding thread and adapted to engage the last named thread of the sleeve, and a stop carried by 110 one of the parts and extending perpendicularly to its axis of rotation and lying in the path of and adapted to meet a portion of one of the other parts in the rotation of the parts relatively, the meeting surfaces of the 115 parts lying substantially parallel to the axis of rotation.

5. A nipple holder comprising a sleeve threaded internally at one end and adapted 120 to receive a nipple at that end and provided internally at its other end with a dissimilar form of thread, a member provided with threads corresponding to the last named threads and adapted to engage the same, a stop carried by and extending from one of 12 the parts perpendicular to the axis of its ro-

tation and lying in the path of a portion of the other part, the surfaces of the stop and said portion lying substantially parallel to the axis of rotation of the parts, and a member separate from the sleeve and the first said member and adapted to lie upon the end of the latter.

In testimony whereof I affix my signature, in presence of two witnesses.

BROWNLOW STARBUCK.
